UNITED STATES PATENT OFFICE.

RAYMOND G. MCKEE, OF DELHI, NEW YORK.

INDUCTION TRANSMITTER.

Application filed June 19, 1922. Serial No. 569,367.

To all whom it may concern:

Be it known that I, RAYMOND G. MCKEE, a citizen of the United States, residing at Delhi, in the county of Delaware and State 5 of New York, have invented new and useful Improvements in Induction Transmitters, of which the following is a specification.

This invention relates to telephonic devices.

More particularly the invention relates to transmitters of the magnetic-induction type.

Some of the objects of the present invention are: To employ magnetic means for 15 setting up a magnetic flux adjacent the vibratory diaphragm to obviate the use of an electrical battery; to employ magnetizable element which is connected to the vibratory diaphragm so that the same may vibrate 20 therewith and means on the opposite side of the vibratory diaphragm for balancing the action of said magnetizable element; to provide means allowing the employment of electrical energy for heavy work; and with 25 these and other objects in view the invention resides in the particular provision, construction, relative disposition and operation of parts hereinafter fully described and illustrated in the accompanying drawing, 30 in which:

Figure 1 is a sectional view taken on a line centrally through the device.

Figures 2 and 3 are sectional views looking in opposite directions from the line 35 *x-x*.

Referring now more particularly to the several views of the drawing for the details, it will be apparent that, the device of the present invention will include a shell 40 10 preferably of brass and open at one end. Arranged inside of the shell are magnets 11. These magnets 11 are of the horseshoe type, each having a relatively long and short leg 12 and 13 respectively. The magnets 11 are connected together in pairs. The short legs 13 of one pair are riveted together as at 14, whereas the short legs 13 of the other pair of magnets are riveted to the riveted short legs of the other pair of magnets. Each long leg 12 of each magnet is secured to the shell 10 by a screw 15. A vibratory thin steel diaphragm 16 is arranged transversely of the shell 10 at the open end thereof, and the said diaphragm 50 lies against the ends of the long legs of the magnets 11 by virtue of which magnetism will flow through said diaphragm. The shell is internally screw threaded to receive the externally screw threaded flange of a cap 17. The flange of the cap 17 is brought 60 into contacting relation with the diaphragm 16 to hold the same securely in place. The cap 17 is made preferably of brass and the same has a central screw threaded hole 65 therein which accommodates the screw threaded end of a mouth-piece 18. In order that a magnetic flux may be set up by the short legs 13 of the magnets 11, there is employed a field-coil 19 which is carried by the said short legs 13. The field-coil 19 comprises a member 20 of iron, and windings 21 of copper wire. The member 20 embodies a recess or pit 22 and a hole 23. There is a screw threaded bore 24 formed 70 in the ends of the legs 13 to accommodate a screw 25 which is passed through the hole 23 in the attachment of the field-coil 19. In the assemblage of the field-coil 19 with respect to the diaphragm the field-coil is in 75 position to readily receive the vibrations of whatever kind leaving the said diaphragm. In order that the vibrations which are set up in the diaphragm may be amplified, and be rendered clear and smooth there is provided means in addition to the magnets 11 80 and the field-coil 19. The means comprises an armature coil 26 connected to one side of the diaphragm, and an element in the nature of a rocker or exciter 27 which balances the action of the coil 26, and produces an 85 effect in the diaphragm to render it properly susceptible to sound waves in the transmission thereof. The coil 26 comprises a metal member 28 and windings of copper wire 29. The member 28 embodies a central 90 part having a screw threaded bore 30 therein, and spaced disks 31 and 32. The disk 32 has a flange 33 and extending axially from said disk is a part 34 which acts as an armature. The element 27 has a knob 10 35 at one end thereof which acts as a weight, and the opposite end of the element is screw threaded to accommodate nuts 36 and the nut 37. The diaphragm 16 has a hole in the axial center thereof which allows the element 27 to be extended therethrough. The screw threaded end is screwed into the bore 30 with the nut 37 disposed between the disk 31 and the diaphragm, whereas, the nuts 36 are disposed on the opposite side of 11

the diaphragm to rigidly hold the parts assembled. In the assemblage of the parts the armature 34 is disposed in the recess or pit 22, and the flange 33 surrounds the field-coil 19 to some extent.

- From the foregoing it will be manifest that means is employed for setting up a magnetic flux in and about the diaphragm which renders the device very sensitive; 10 that by employing a balanced armature coil on the diaphragm in conjunction with the field-coil and permanent magnets the diaphragm and armature-coil may be much further magnetized, with increased results 15 in the field-coil, when the sound waves cause the diaphragm to vary the distance between the coils. This variation between the two coils in effect is similar to the effect of an alternating current generator on a 20 very small scale.

The shell 10 is provided with binding posts 38. There are preferably four binding posts. The ends of the windings 21 are connected to two of the binding posts which 25 latter are also connected in the line. If desired, to carry out heavy work, the ends of the windings 29 may be connected to a source of electrical energy by virtue of the other two binding posts 38. 30 It should now be manifest that the transmitter of the present invention may be used for instance directly in an arc transmitting circuit. It may be used to render radio systems more thoroughly efficient because of its non-microphonic effects. The 35 device can also be perfected so that the use of a battery is obviated.

While there has been shown the preferred embodiment of the invention, it is to 10 be understood that, changes, alterations and modification within the scope of the claims hereunto appended may be resorted to whenever it is deemed necessary or desirable.

45 What is claimed is:

1. A telephonic device of the character described comprising a vibratory diaphragm, an armature coil carried by said diaphragm, a rocker exciter passing 50 through the diaphragm and having its inner end secured to the armature coil, a weight formed on the outer end of the rocker exciter to balance the armature coil and means for magnetizing said diaphragm and said armature coil respectively.

2. A telephonic device comprising a shell, a vibratory diaphragm held in place in said shell, permanent magnets arranged 55 at an angle with respect to said vibratory diaphragm, one pole of each of said permanent magnets touching said diaphragm, a field-coil, one pole of each of said permanent magnets touching said field-coil, a magnetizable element in magnetizable relation to said diaphragm, and an element con-

nected to said diaphragm and to said magnetizable element for balancing the action of said magnetizable element.

3. A telephonic device including a vibratory diaphragm, juxta-posed magnetic elements at one side of the diaphragm, one of said magnetic elements being slightly larger than the other of said magnetic elements and having a portion overlying the latter element, means passing through said diaphragm and connected with the larger of said magnetic elements and supporting the same and connecting it with the diaphragm, and said means being weighted at the side of the diaphragm opposite that at which the magnetic elements are disposed, for balancing the action of said element connected to the diaphragm.

4. A telephonic device including a vibratory diaphragm, juxta-posed magnetic elements at one side of said diaphragm, said magnetic elements being substantially in the shape of disks, one of said magnetic elements being of slightly greater diameter than the other of said elements, the larger of said elements having an annular flange surrounding a portion of said smaller element, means passing through said diaphragm and connected with the larger of said magnetic elements, and supporting the same and connecting it with the diaphragm, and said means being weighted at the side of the diaphragm, opposite that at which the magnetic elements are disposed, for balancing the action of said elements connected to the diaphragm.

5. An induction transmitter including a magnetized vibratory diaphragm, a magnetizable element at one side of said diaphragm and connected thereto, and a field coil arranged adjacent said magnetizable element, a weighted rocker exciter passing through the diaphragm and associated with the field coil as and for the purpose specified.

6. A telephonic device comprising a shell, a vibratory diaphragm held in place in said shell, permanent magnets in the shell, one pole of each of said permanent magnets touching said diaphragm, a field coil, the other pole of each of said permanent magnets touching said field coil, and an armature coil in magnetizable relation to said diaphragm, and a weighted rocker exciter passing through the diaphragm and secured to the armature coil for balancing said armature coil with respect to the field coil and diaphragm.

7. A telephonic device comprising a shell, a vibratory diaphragm held in place in said shell, permanent magnets in the shell, one pole of each of said permanent magnets touching said diaphragm, a field coil, the other pole of each of said permanent magnets touching said field coil, and an arma-

ture coil disposed between said diaphragm and said field coil and in magnetizable relation to said diaphragm, and a weighted exciter passing through the diaphragm and 5 being secured to the armature coil.

8. A telephonic device comprising a shell, a vibratory diaphragm held in place in said shell, permanent magnets, one pole of each of said permanent magnets touching said 10 diaphragm, a field coil, the other pole of each of said permanent magnets touching

said field coil, an armature coil arranged between said diaphragm and field coil and in magnetizable relation to said diaphragm, and an element connected to said diaphragm 15 and to said armature coil and weighted at the side of the diaphragm opposite that at which the armature coil is disposed, for balancing the action of the armature coil.

In testimony whereof I hereby affix my 20 signature.

RAYMOND G. McKEE.
